WINDOW STRUCTURE

Filed Nov. 26, 1923

UNITED STATES PATENT OFFICE.

JOSEPH C. WEGSTEIN, OF WASHBURN, ILLINOIS.

WINDOW STRUCTURE.

Application filed November 26, 1923. Serial No. 676,946.

To all whom it may concern:

Be it known that I, JOSEPH C. WEGSTEIN, a citizen of the United States, a resident of Washburn, in the county of Woodford and State of Illinois, have invented new and useful Improvements in Window Structures, of which the following is a specification.

This invention has reference to window structures and it has for its principal object to improve that type of structure having a head space or head pocket into which both the upper and lower sashes may be telescoped, whereby to leave a free and unobstructed window opening.

The invention has for a further object means for latching the upper sash in its normal position in the window casing, and means on the lower sash for releasing said latching means upon the raising of the lower sash, whereby it is made possible to telescope both said sashes into the head space or pocket, or to lower the upper sash in parallel relation to the lower sash.

A further object of the invention is to provide latching means to hold the upper sash in its normal position in the casing, which comprises latch members pivotally held in opposite sides of the window casing and yieldable means for holding said latch members in locking position; said latch member cooperating with complementary means on the upper sash, and means being provided on the lower sash to release said latch members on the raising of the lower sash.

That the invention may be more fully understood, reference is had to the accompanying drawings, forming a part of the present description, illustrating a preferred embodiment of the invention, in which:

Figure 1 is a vertical cross-section through a window casing and upper and lower sash, partly broken away showing my invention embodied therein;

Figure 2 is a front elevation, partly in section and partly broken away of one side of the window casing and upper and lower sash showing the latching and releasing means therefor, the sashes shown in their normal positions, as the same would appear looking in on the line 2-2 Figure 1;

Figure 3 is a view somewhat similar to Figure 2 except that the lower sash is shown raised and the latching means released;

Figure 4 is a vertical sectional view of a latch, and

Figure 5 is a cross-section as the same would appear if taken on the line 5-5 Figure 4.

Like characters of reference denote corresponding parts throughout the figures.

Reference being had to Figures 1 and 2 there is illustrated the general structural arrangement of a window casing and upper and lower sashes therein, together with the sash cords and pulleys for balancing said sashes, and only such detailed reference will be made to the individual elements thereof as may be necessary to show the application of my invention and its operation.

The casing includes the sill 1; sill piece 2; inside bead 3; outside bead 4; parting bead 5; cross-piece 6 and finish 7. Slidable along stiles or jambs 8 are the lower and upper sashes 9 and 10, having the meeting rails 9^a and 10^a. Between the inside wall structure A and the sheathing and weatherboard structure B, above the main casing for the sashes is provided a head space or head pocket C into which extend the stiles 8 and the parting bead 5 forming a runway for the telescoping of the sashes 9 and 10 into said head space or pocket C, as shown in dotted lines in Figure 1. At the extreme upper end of the head space or pocket C and within the stiles are located sash pulleys 11 to receive the sash cords 12 and weights, not shown, for counterbalancing the sashes, in a manner well known, and above the sash pulleys is a head frame 13.

Secured to the upper edge of the top sash 10 is a head piece 14 which projects forward of said sash in manner seen in Figure 1, crossing the parting bead 5 and extends across the stile in which the lower sash 9 slides.

This head piece 14, when the upper sash is in its normal position, serves as a "head frame" for the casing and together with the cross piece 6 gives the proper finish to the casing and presents a completed appearance when viewing the casing and sashes from the inside. The opposite ends of the head piece 14 are beveled, as at 15, see Figures 2 and 3, for purposes to be explained.

Secured in and to the parting beads 5 at a point in the casing in the rear of the cross piece 6 of the casing, and which is at points

corresponding to the normal position of the top rail of the upper sash 10, are latch retaining housings 16. These housings are preferably upstanding elongated U shaped metal strips which are held in place by screws 17, see Figure 4 and the upper ends of said housings are closed by bent metal head strips 18 which overlie the upper front open ends of said housings, as shown, which 5 act as stops for the latches. The latches are designated 18' and are substantially upstanding U shaped members bent into form from sheet metal and are inverted in relation to the housings and pivoted therein, at 10 their lower ends by means of pivot rods 19 and carried around these rods are flat spring members 20 with ends bearing, respectively, against the latches and the inside rear wall of the housings, see Figure 4, and act to normally 15 hold the latches projecting outwardly from the housings, at an inclination, as shown; their outward movement being limited by the head strips 18, as will be understood. The upper front walls of the latches 20 are inclined rearwardly to present sloping surfaces 21 and at the base of said sloping surfaces slots 22 are provided, extending transversely of said latch members to receive complementary members on the upper sash 25 to lock or hold the same in normal position. When the latches 18 are in locking position the inclined positions in which they are held 30 present oppositely inclined surfaces, the tapered surface 21 and the main surface of the latch which is inclined in relation to the front wall of the housings, and also provide sloping surfaces on which the coacting means, to be described, of the upper and lower sashes may ride when the upper sash 35 is moved to locking position and when the lower sash is moved to release the latches.

To the opposite lower ends of the head piece 14 are connected plates 23 which project beyond the lower sloping ends 15 of 40 said head piece and are adapted to enter the slots 22 in the latches to lock the upper sash in its normal position. To the opposite ends of the top rail 9^a are connected angular plates 23' which are adapted to ride against 45 the latches when the lower sash is raised, to release the latches from the plates 23 on the upper sash.

Reference being had to Figure 1 it will be seen that the angular plates 23' normally 50 overlie the lower rail 10^a of the upper sash but without a binding effect on the front face of said upper sash when the lower sash is raised. These overlying plates have for their purpose to insure the upper sash being 55 drawn downward from the head space or pocket C, on lowering the lower sash.

In operation, assuming that the sashes 9 and 10 are in their normal position, shown 60 in Figures 1 and 2 and it is desired to telescope both said sashes into the head space

of pocket C to leave an unobstructed opening throughout the window casing, the lower sash 9 is raised bringing the angular plates 23' into contact with the latches and said plates riding over their front faces will 65 cause the same to be moved back into the housings, or from the dotted line position in Figure 4 to the full line position in said figure and Figure 3, which movement will release the latches from the locking plates 23 70 on the sash 10. On the release of the locking plates on the upper sash the releasing plates on the lower sash have been moved up into 75 position with the angle of the plates 23' disposed between the beveled ends of the head 80 piece 14 and the casing of the window. The further upward movement of the lower sash, having a bearing as it will with the head piece 14 on the upper sash, will cause said upper sash to be raised with the lower sash 85 into the head space or pocket C, as shown in dotted lines in Figure 1. To lower the upper sash 10 to a position behind the lower sash, within the window casing, the latches are released in the manner just described 90 when the two sashes may be lowered to the position desired in the casing. As will be obvious, the latches serve as locks to secure the upper sash in the casing, which however, need not dispense with the usual sash 95 locks.

The hardware provided, as will be seen, is of the simplest form yet practical and efficient and may be produced at the lowest 100 possible cost.

What I claim is:—

1. In a pocket window structure, in combination, an upper and a lower sash adapted to be telescoped into the pocket of the window, a head piece connected with the top rail of the upper sash and overlying and adapted to be engaged by the lower sash when raised, latch members pivoted to the window casing, means to yieldably hold said latch members in locking position, complementary means on said head piece arranged to have a locking engagement with said latch members, and means connected to the lower sash arranged to have a slidable relation with said latching members for releasing the same when the lower sash is raised.

2. In a window structure and in combination with the upper and lower sashes, of means for locking the upper sash in normal position and for releasing said locking means by and with the raising of the lower sash, comprising housings for securement in the window casing, yieldable latches pivoted in said housings, plates on the upper sash arranged to have a locking relation with said latches, and angle plates on the lower sash adapted to have a slidable relation with said latches when the lower sash is raised, whereby to release said latches.

3. In a sash structure for pocket windows, in combination, an upper and a lower sash, a head piece connected with the top rail of the upper sash and projecting therefrom throughout its length to overlie and be engaged by the lower sash, whereby the two sashes may be raised together, means to lock

the upper sash in normal position, and means on the lower sash to release said locking means during the raising of the lower sash and for drawing down the upper sash from the pocket when lowering the lower sash. 10

In witness whereof, I have hereunto affixed by hand this 24th day of November 1923.

JOSEPH C WEGSTEIN.
